US00D909234S

(12) **United States Design Patent** (10) Patent No.: **US D909,234 S**
(45) Date of Patent: **** Feb. 2, 2021**

(54) **PENDANT**

(71) Applicant: **Richemont International SA**,
Villars-sur-Glaine (CH)
(72) Inventor: **Stephanie Sivriere**, Geneva (CH)
(73) Assignee: **Richemont International SA**,
Villars-sur-Glaine (CH)
(**) Term: **15 Years**

(21) Appl. No.: **29/693,503**

(22) Filed: **Jun. 3, 2019**

(30) **Foreign Application Priority Data**

Dec. 4, 2018 (WO) 970003114

(51) **LOC (13) Cl.** **11-01**
